DESIGN FOR A CLOTHES HAMPER

Otto Eidinger, Chicago, Ill., assignor to Hydro-Tex Corporation, a corporation of Illinois

Application July 2, 1941, Serial No. 101,860

Term of patent 3½ years

To all whom it may concern:

Be it known that I, Otto Eidinger, a citizen of the United States, residing at Chicago, in the county of Cook and State of Illinois, have invented a new, original, and ornamental Design for a Clothes Hamper, of which the following is a specification, reference being had to the accompanying drawing, forming a part thereof, in which:

Figure 1 is a top plan view of a clothes hamper showing my new design; Figure 2 is a front elevational view of the same; and Figure 3 is a side elevational view.

I claim:

The ornamental design for a clothes hamper, as shown.

OTTO EIDINGER.
